UNITED STATES PATENT OFFICE.

GEORGE EZRA MAXWELL, OF BRONAUGH, MISSOURI.

UPSETTING ATTACHMENT FOR VISES.

1,087,388.

Specification of Letters Patent. Patented Feb. 17, 1914.

Application filed June 26, 1912. Serial No. 706,055.

To all whom it may concern:

Be it known that I, GEORGE E. MAXWELL, a citizen of the United States, residing at Bronaugh, in the county of Vernon and 5 State of Missouri, have invented new and useful Improvements in Upsetting Attachments for Vises, of which the following is a specification.

This invention relates to devices for shrinking and upsetting tires and the like, and it has for its object to provide a simple, inexpensive and efficient upsetting device which may be readily applied to and used in 10 connection with a blacksmith's vise of ordinary construction.

A further object of the invention is to provide a simple and inexpensive upsetting device which when not in use may be easily and quickly detached from the vise and stored 15 in small compass.

With these and other ends in view which will readily appear as the nature of the invention is better understood, the same consists in the improved construction and novel 20 arrangement and combination of parts which will be hereinafter fully described and particularly pointed out in the claim.

In the accompanying drawing has been 25 illustrated a simple and preferred form of the invention, it being, however, understood that no limitation is necessarily made to the precise structural details therein exhibited, but that changes, alterations and modifications within the scope of the claim may be 30 resorted to when desired.

In the drawing,—Figure 1 is a perspective view showing the invention applied to an ordinary vise. Fig. 2 is a top plan view showing a portion of a tire applied in position to be operated upon. Fig. 3 is a side elevation illustrating a modified form of the invention, and also showing a portion of a tire in position to be operated upon. Fig. 4 is a top view of the same.

45 Corresponding parts in the several figures are denoted by like characters of reference.

The improved upsetting attachment is composed of two members A and B adapted to be mounted, respectively, upon the movable jaw C and upon the stationary jaw D of an ordinary blacksmith's vise, said vise being equipped with a screw E for forcing the movable jaw in the direction of the stationary jaw. The jaws are forced 50 apart in the customary manner by means of a spring F. The members A and B are

each composed of a base plate 1, said base plates being provided adjacent to their inner or meeting edges with downward extending flanges 2 adapted to engage the faces of the 60 vise jaws. Each of the base plates 1 is also provided adjacent to its outer edge with a downwardly extending flange 3 adapted to rest externally upon the vise which is usually provided with an enlargement or offset 65 4 upon which the flange 3 may be supported. In the absence of such offset, however, the flange 3 may be supported upon the body of the jaw.

Under the construction illustrated in Figs. 70 1 and 2 the base plates 1 are provided adjacent to one of their side edges with upwardly extending flanges 5 having teeth or corrugations, as shown at 6. Pivots 75 mounted upon each of the base plates 1 near the outer edge thereof is a cam lever 7 having a corrugated or toothed engaging face 8 and a handle 9 which extends a suitable distance beyond the edge of the base plate opposite to that having the flange 5 so as to be readily grasped by the operator standing 80 in front of the vise or at one side of the latter.

In the operation of this device the members A and B are placed upon the jaws of 85 the vise, while said jaws are separated or spaced apart, and the tire or article to be shrunk or upset is then placed upon the base plates 1 between the flanges 5 and the cam levers, the latter being actuated to grasp 90 or secure the article between the corrugated faces of the flanges 5. The article may be steadied by the hand of the operator, while the screw E of the vise is actuated to force the movable jaw in the direction of the stationary jaw, thereby causing the article to be shrunk or upset, as will be readily understood.

Under the slightly modified construction 95 illustrated in Figs. 3, 4 of the drawings the base plates here designated 1' of the members A and B are corrugated upon their upper faces, said base plates being provided adjacent to one of their side edges with upstanding flanges 5' upon which the cam 100 levers, here designated by 7', are pivotally mounted. The handles 9' of said cam levers will thus extend upwardly instead of laterally from the vise, which may sometimes be found desirable. In other respects the construction and operation are precisely as hereinbefore described.

As will be seen from the foregoing description, the improved upsetting attachment is extremely simple in construction and is capable of being produced at a very 5 moderate expense. The said device may be very readily applied to any ordinary blacksmith's vise without the use of any special fastening means, and it follows that the device may be applied or detached in a 10 few moments. By this invention, the use of a special upsetting machine, the cost of which greatly exceeds that of my improved attachment, may be dispensed with.

Having thus described the invention, what 15 is claimed as new, is:—

An upsetting device for vises including a

pair of base plates, one of the plates being adapted to be disposed upon each jaw of the vise, downwardly extended flanges projecting from the inner ends of the plates and 20 adapted to engage the meeting faces of the vise, downwardly extended supporting legs projecting from the outer ends of said base plates and adapted to engage the sides of vise, and clamping levers for securing the 25 work to the base plates.

In testimony whereof I affix my signature in presence of two witnesses.

GEORGE EZRA MAXWELL.
